UNITED STATES PATENT OFFICE.

J. TALMAN BUDD, OF BUFFALO, NEW YORK.

SUSPENDERS.

SPECIFICATION forming part of Letters Patent No. 339,968, dated April 13, 1886.

Application filed December 26, 1885. Serial No. 186,716. (No model.)

To all whom it may concern:

Be it known that I, J. TALMAN BUDD, a citizen of the United States, residing at Buffalo, in the county of Erie and State of New York, have invented certain new and useful Improvements in Suspenders; and I do hereby declare the following to be a full, clear, and exact description of the invention, such as will enable others skilled in the art to 10 to which it appertains to make and use the same, reference being had to the accompanying drawings, and to letters or figures of reference marked thereon, which form a part of this specification.

15 My invention consists of a certain improved construction of pants-supports for suspenders, which will be more fully hereinafter described and claimed.

In the drawings, Figure 1 shows my improvements attached to the back of the suspenders. Fig. 2 shows my improvements attached to the front of suspenders. Figs. 3, 4, and 5 are views of modifications.

Referring to the drawings, *a a* are the rear 25 ends of the shoulder-straps, which are joined together by the supporting material *b*, which incloses such ends, forming the bend *b'* at its lower end. Within this bend *b'* rests the upper bar of the hanger *c*, and interposed between the bar and the supporting material is the loose friction-tube *d*.

In Fig. 4 is shown a similar application of the friction-tube *d* to the non-adjustable supporting material *e*, in which are rigidly enclosed the flexible ends *e'* of the pants-supports adapted for front or rear attachment to the shoulder-straps.

In Fig. 5 is shown, in place of the friction-tube *d*, a friction-shield, *f*, consisting of a 40 piece of metal bent to partially encircle the suspending bar of the hanger. This friction tube or shield *d* or *f* just described serves to relieve the supporting material *b* or *e* from frictional contact with the hanger, thereby increasing its durability.

g g, Fig. 1, are the flexible ends of the pants-supports, preferably formed from any suitable fabric. These flexible ends are joined together and adjustably connected with the 50 hanger *c* by the strips *g' g'*, preferably formed of leather or rubber. The strip *g'* passes over

the middle bar of the hanger *c*, and the strip *g''* passes over the lower bar of the hanger *c*, each strip being fastened one end to the front and one to the rear of each flexible end.

55

In Fig. 2 the pants-supports, just described are shown connected with a hanger adapted for front connection with the suspenders.

In Fig. 3 are shown the fabric ends *g g*, attached by a single strip, *h*, preferably formed 60 of leather or rubber, which is adjustably connected with a hanger.

In suspenders there are pants-supports adjustable and with limited adjustability, but being constructed all from one material, which 65 either will not stand the wear of adjustability as when constructed of fabric, or which is not entirely suitable for the formation of button-holes, as when leather or rubber is employed.

In using suspenders with the adjustable attachment to flexible ends free movement of the body can be had without strain upon the different ends and buttons, as when non-adjustable attachments are used, and the combination of adjustable attachments with flexible ends permits the use of material suitable 70 for attachment to pants in connection with other material which is suitable to stand the friction and wear of automatic adjustability.

75 I claim—

1. In suspenders, in combination with a hanger for attachment to shoulder strap or straps, flexible fabric ends for pants or drawers supports provided with an adjustable attachment consisting of a strip or strips of 85 leather or other suitable material rigidly attached to flexible fabric ends and adjustably attached to a hanger, substantially as shown and described.

2. In suspenders, the pants or drawers supports consisting of the flexible fabric ends, *g g*, and the strips *g' g''*, of leather or other suitable material, rigidly attached to the fabric ends *g g*, and adjustably attached to a hanger, substantially as shown and described.

90 95 In testimony whereof I have signed my name to this specification in the presence of two subscribing witnesses.

J. TALMAN BUDD.
